ABSTRACT

A pair of disc-shaped seats are supported in a horizontal relationship by a suspended cable having each of its ends attached to the central portion of a seat. The cable is threaded over a pair of overhead supported, horizontal disposed pulleys. The cable, pulley and seat arrangement is supported such that any downward movement of one seat produces an upward movement of the other seat. The seats are suspended for simultaneous up-horizontal and down-horizontal movements.

FIG. 3.

FIG. 1.

FIG. 2.

**1
SEE-SAW SWING APPARATUS****SUMMARY OF THE INVENTION**

The invention is directed towards a swing which combines the best features of a swing and a see-saw. The object of the invention is to provide a swing which allows each of a pair of users to swing freely in two dimensions, and at the same time allows one user to raise or lower the height of the other user's seat by lowering or raising the height of his own.

Thus, a like pair of discs are supported by a single cable which is attached at each end to the center of a disc.

The cable is supported by a frame which allows the cable to move in a manner that the downward motion of one of the seats moves the cable to cause a like upward motion of the other seat. Because the ends of the cable hang downwardly under the influence of gravity, each disc is free to rotate about the cable and to swing in any vertical plane. When a pair of users are sitting on the seats, one user can raise or lower the seat height of the other user by lowering or raising his own seat height.

BRIEF DESCRIPTION OF THE DRAWINGS

In the drawings:

FIG. 1 is a side view of the invention;
FIG. 2 is a top view of the invention; and
FIG. 3 is a drawing of a portion of the invention.

DETAILED DESCRIPTION OF PREFERRED EMBODIMENTS

Referring now to the drawings, a cross bar 10 is dis-

2

posed in a horizontal plane and supported at each end by an A shaped support 20. The cross bar supports a carrier 30 which supports two like pulleys 40 in a manner that they are free to rotate in a common vertical plane. A cable 50 is supported by the pulleys and is run through two guides 60, each of which takes the form of a hollow elongated cylinder with a central vertical bore in which the cable is disposed. The ends of the cable are attached to the centers of each of two like discs 70 which serve as seats.

While the invention has been described with detailed reference to the drawings, the protection sought is to be limited only by the terms of the claims which follow.

I claim:

1. A swing comprising:
a frame having a pair of spaced apart vertically up-standing supports and an elongated horizontal support bar connected at its ends to the upper end of the supports;
a pair of spaced apart pulleys being attached to said support bar and being disposed in a common plane;
a cable, said cable being passed over said pulleys such that each of its ends is freely suspended below a respective pulley; and
a pair of seats, each end of said cable being centrally attached to a seat such that each seat is free swinging when supported by said cable and any upward movement of one seat produces a corresponding downward movement of the other seat.
2. The swing of claim 1 wherein the seats are disc shaped.
3. The swing of claim 1 wherein said pulleys are disposed perpendicular to said horizontal support bar.
